UNITED STATES PATENT OFFICE.

THOMAS TROLSEN, OF BROOKLYN, NEW YORK.

CONTROLLER FOR ELECTRIC-MOTOR-DRIVEN PUMPS.

SPECIFICATION forming part of Letters Patent No. 718,177, dated January 13, 1903.

Application filed July 5, 1902. Serial No. 114,449. (No model.)

To all whom it may concern:

Be it known that I, THOMAS TROLSEN, a citizen of the United States, and a resident of the borough of Brooklyn, county of Kings, 5 State of New York, have invented certain new and useful Improvements in Controllers for Electric-Motor-Driven Pumps, of which the following is a specification.

My invention relates to a controller for 10 electric-motor-driven pumps, and particularly to pumps of the kind employed to supply water to hydraulic elevators or tanks in the basement or floors of buildings to supply water for drinking, flushing, washing and other purposes.

In systems or devices relating to the controlling of motor-driven pumps considerable loss is occasioned by the friction which it is necessary to overcome and by the fact that 20 the systems are not so adjusted as to permit of operation unless there is a considerable variation in pressure of the water in the tank. Among other things my invention aims to eliminate this friction and to reduce to the 25 lowest practicable minimum the variation of tank-pressure.

To accomplish the objects of my invention, I have devised a system illustrated diagrammatically in the accompanying drawing, to 30 which reference will now be made and the essential features thereof pointed out in the claims.

A designates a motor to which is connected any suitable form of pump for filling the tank 35 A' with water. The tank A' may be located in any desired location, as the roof or upper floor or in the basement of a building, from which tank water is distributed through suitable outlets. In order to control the operation of the motor through the pressure of the water in the tank, I provide in the circuit which includes the motor A an electromagnet 40 B, a pilot-electromagnet C, a rheostat D, a rheostat-arm E, and mercury-contact cup F. Except when otherwise stated these elements 45 are of any usual or ordinary construction and their mode of operation well understood. In the drawing the various parts are shown in position when the motor is at rest and when 50 the pressure of water in the tank A' is above that which necessitates further filling. The tank A' is connected with a pressure-regula-

tor a of any approved construction by a pipe a', and when the pressure in said tank is lowered to a predetermined point the lever a² of 55 the regulator, which is pivoted at a³ on the regulator-frame, is lowered, thereby lowering the connected contact-pin f into the mercury of the cup F, thus closing the circuit through the motor and starting the pump in operation. The pump continues to fill the tank A' until the desired pressure is reached, when the lever a² is raised, thereby raising the pin f and breaking the circuit, when the parts resume their normal positions, as shown in 60 the drawing. The pin f is preferably made of metal and is connected to the lever a² by a suitable chain f', from which it is insulated, and to a flexible conductor f², which latter is connected to the terminal o of the circuit 1. 70

The core C' of the magnet C is provided with two contact-plates c and c', made of some suitable conducting material and suitably insulated from each other and from the core C'. These plates are adapted to contact, respectively, with terminals o' o² and o³ o⁴. When the metallic pin f comes in contact with the mercury in the cup F, the circuit 1 is closed, thus energizing the magnet C and drawing inwardly the core C'. This brings the plate 80 c into contact with the terminals o' o² and the plate c' into contact with the terminals o³ o⁴. The current from line M then traverses circuit 2 through the rheostat D and rheostat-arm E to the motor A and out through 85 the terminals o³ o⁴ to line N. The magnet B is included in the circuit 3, comprising terminals o⁵ o⁶ and spring-contact O. The core B' of the magnet B is connected by suitable means to the rheostat-arm E. When the coil 90 B is energized, the said arm is raised and passes to the extreme end of the rheostat for the maximum speed of the motor. Before the rheostat-arm E reaches the limit of its upward movement the plate e' on said arm 95 contacts with the terminal o⁷, thus cutting in the local circuit 4, which includes the lamp L. Continued upward movement of the arm E causes the extension e of said arm to raise the spring-contact O from the terminal o⁵, 100 thus cutting out the circuit 3 through magnet B and allowing only sufficient current through the local circuit 4 to maintain the arm E at the upper limit of its movement.

The arm E remains in its uppermost position until the maximum pressure in the tank is reached, when the pin f is raised, breaking all the circuits and permitting the several parts to resume their normal positions.

5 The lamp L in the circuit 4 provides a resistance to prevent burning out of the coil B, and the lamp L' reduces to a minimum the sparking in the mercury-cup F and prevents 10 burning out of the coil C.

A dash-pot G is provided for the arm E to permit its gradual ascent.

In prior systems the lever a^2 of the regulator was provided with a terminal plate, 15 which made frictional engagement with the terminals of the circuit. This necessitated certain work to be done in order to overcome the friction. By the employment of a mercury-cup I do away entirely with frictional 20 contacts, and by the use of such cup in connection with the magnet C to do the preliminary work of closing the circuits through the main magnet B, I provide a much more delicate system and one in which a difference of 25 three or four ounces of pressure in the tank A' is sufficient to operate the motor, whereas in systems heretofore employed a difference in the pressure in the tank A' of from ten to fifteen pounds was necessary to start the 30 motor in operation.

My invention introduces a method of operating electric-motor-driven pumps, which, as compared with the methods now in vogue, is much more simple and effective, besides being less expensive in its construction and operation.

What I claim, and desire to secure by Letters Patent, is—

1. In a controller for electric-motor-driven 40 pumps, the combination of a pilot-electromagnet, two independent contact-plates on the core of said magnet, a mercury-cup, a contact therefor and means to control the movement of said contact, a circuit including said 45 magnet and cup, a circuit controlled by said contact-plates and a motor included in said circuit.

2. The combination with an electric motor 50 of means for controlling the operation of the same comprising a mercury-cup, a contact therefor, a pressure-regulator to control the movement of said contact, a pilot-electromagnet and suitable circuits controlled by said magnet.

55 3. The combination with an electric motor of means for controlling the operation of the

same comprising a mercury-cup, a contact therefor, a pressure-regulator to control the movement of said contact, a pilot-electromagnet, two independent contact-plates on the 60 core of said magnet and suitable circuits.

4. In a controller for electric-motor-driven pumps, the combination of a pilot-electromagnet and means to energize the same, two independent contact-plates on the core of said 65 magnet, circuits controlled by said contact-plates, a motor included in one of said circuits, an electromagnet included in the other of said circuits, a local circuit for said last-named magnet, and means to cut out the main 70 circuit of said last-named magnet after the local circuit has been cut in.

5. In a controller for electric-motor-driven pumps, the combination of a pilot-electromagnet and means to energize the same, two 75 independent contact-plates on the core of said magnet, circuits controlled by said contact-plates, a motor included in one of said circuits, an electromagnet included in the other of said circuits, said motor-circuit including 80 a rheostat the arm of which is connected to the core of said last-named magnet.

6. A controller for electric-motor-driven pumps comprising a rheostat, a rheostat-arm, a magnet to control the movement of said 85 arm, a main and a local circuit for said magnet, a contact-plate on said arm adapted to contact with the terminal of said local circuit and a spring-pressed contact in said main circuit adapted to be engaged by said arm. 90

7. In a controller for electric-motor-driven pumps, the combination of a pilot-electromagnet and means to energize the same, two independent contact-plates on the core of said 95 magnet, circuits controlled by said contact-plates, a motor included in one of said circuits, an electromagnet included in the other of said circuits, a local circuit for said last-named magnet, an arm connected to the core of said last-named magnet included in the 100 motor-circuit, and suitable contacts included in the main and local circuits of said magnet, whereby by the movement of said arm the said main circuit will be cut out after the local circuit has been cut in. 105

In testimony whereof I have signed my name to this specification in the presence of two subscribing witnesses.

THOMAS TROLSEN.
